Primary Examiner — Prabhakar Deshmukh(74) *Attorney, Agent, or Firm* — Leydig, Voit & Mayer, Ltd.(57) **CLAIM**

The ornamental design for a game target, as shown and described.

DESCRIPTION

FIG. 1 is a side perspective view of a first embodiment of a game target showing my new design;

FIG. 2 is a front side elevational view of the game target shown in FIG. 1, the right, left and rear sides being the same; FIG. 3 is a top plan view of the game target shown in FIG. 1; FIG. 4 is a bottom plan view of the game target shown in FIG. 1;

FIG. 5 is a perspective view of the game target in FIG. 1, here shown collapsed;

FIG. 6 is a side perspective view of a second embodiment of a game target showing my new design;

FIG. 7 is a front side elevational view of the game target shown in FIG. 6, the right, left and rear sides being the same; FIG. 8 is a top plan view of the game target shown in FIG. 6; and,

FIG. 9 is a bottom plan view of the game target shown in FIG. 6.

The broken line showing in FIGS. 1, 2, 6, and 7 is included for illustration purposes only and forms no part of the claimed design.

1 Claim, 9 Drawing Sheets(56)
